UNITED STATES PATENT OFFICE.

CLARA E. CARR AND GEORGE D. SCOTT, OF NEW YORK, N. Y., EXECUTRIX
AND EXECUTOR OF WILLIAM S. CARR, DECEASED.

VALVE FOR WATER-CLOSET CISTERNS.

SPECIFICATION forming part of Letters Patent No. 252,735, dated January 24, 1882.

Application filed October 22, 1881. (No model.)

To all whom it may concern:

Be it known that WILLIAM S. CARR, late of the city and State of New York, now deceased, did invent an Improvement in Valves 5 for Water-Closet Cisterns, of which the following is a specification.

The object of this invention is to dispense with the service-box in water-closet cisterns, and at the same time prevent the waste of 10 water.

This improvement is adapted to allow the water to flow gradually from the cistern after the valve thereof has been raised by a pull, or by an additional sleeve. The same valve is 15 adapted to a hopper water-closet, in which the cistern-valve is lifted by the depression of the water-closet seat, and the water does not run until the seat is released.

In the drawings, Figure 1 is a vertical section of the valve and its appliances, and Fig. 20 2 is a sectional plan at the line *x x*.

The cylinder *a* is provided with a flange, 1, beneath the bottom *b* of the cistern, and the upper end of said cylinder *a* passes through 25 the cistern-bottom and forms a valve-seat. The nut and washer 2 serve to connect the cylinder firmly to the cistern. At one side of the cylinder *a* there is a coupling, *d*, and pipe leading to the water-closet. A cylinder, *e*, is 30 screwed to the bottom of the cylinder *a*, and its interior surface is larger than the tube *f*. The air and overflow tube *f* is finished off smooth at its lower end to slide in the contracted lower end of the cylinder *a*, and it has 35 a small valve, *i*, at the otherwise closed lower end opening outwardly, so that when the tube *f* is raised water may flow into the cylinder *e*, and such water-cylinder *e* will act as a dash-pot or variable chamber to prevent the tube *f* 40 descending rapidly, because the valve *i* closes and the water is sufficiently confined to prevent the tube *f* descending rapidly, in order that the valve *h* that is carried by the tube *f* may remain open the proper time before it 45 closes upon the seat at the upper end of the cylinder *a*.

It is to be understood that the water in the cylinder *e* will pass gradually up through the small space left between the outside of the 50 tube *f* and the contracted part of the cylinder *a* as the tube and valve descend.

The tube *f* is slotted below the valve *h* for the passage of water from the cistern to the pipe leading to the closet, and this tube *f* is to be lifted either by the water-closet pull or by a 55 connection to the seat of the hopper water-closet, such connections being the ordinary levers and wires or chains. Hence if a pull is used it will be lifted and then dropped, and the tube *f* and valve are raised and descend 60 gradually, allowing the water to run to the closet in the required quantity; but if a hopper-closet and hinged seat are used the water would continue to run as long as the seat was depressed. The slotted portion of the tube *f* is 65 therefore surrounded with a sliding sleeve, *n*, to which the wire *o* is connected, and by which the tube *f* is lifted. Hence when the closet-seat is depressed the sleeve *n* is moved up to the valve *h* and lifts the same, and the tube 70 *f* and said sleeve *n* keep the slots in the tube *f* covered, so that water cannot flow to the closet because the sleeve *n* also fills the opening of the valve-seat; but as soon as the pressure on the seat of the closet is removed the 75 sleeve *n* falls by gravity and allows the water to run, as before set forth, until the tube *f* gradually descends and the valve *h* closes upon its seat, as aforesaid.

What is claimed as the invention of the said 80 WILLIAM S. CARR is—

1. The combination, in a cistern-valve for water-closets, of the cylinder *a*, pipe to the water-closet, water-cylinder *e*, tube *f*, valve *h* around the same, and small valve *i* at the lower 85 end, substantially as and for the purposes set forth.

2. The sleeve *n*, sliding upon the slotted portion of the tube *f*, and to which sleeve the wire or connection to the water-closet is attached, in combination with the valve *h*, cylinder *a*, water-cylinder *e*, and seat for the valve *h*, substantially as set forth. 9c

Signed by us this 21st day of December, A. D. 1880.

CLARA E. CARR, *Executrix.*
GEORGE D. SCOTT, *Executor.*
